[57] CLAIM

The ornamental design for a squeegee blade offset carrier, substantially as shown.

DESCRIPTION

FIG. 1 is a top view of the squeegee blade offset carrier, showing my new design.

FIG. 2 is a right side view thereof, the opposite side view being a mirror image thereof.

FIG. 3 is a bottom view thereof.

FIG. 4 is a rear view thereof.

FIG. 5 is a front view thereof.

FIG. 6 is a top isometric view thereof.
